UNITED STATES PATENT OFFICE.

LEWIS J. GREENAWALT, OF MANSFIELD, OHIO, ASSIGNOR TO WESTINGHOUSE ELECTRIC PRODUCTS COMPANY, A CORPORATION OF MICHIGAN.

CARTRIDGE-HEATER TERMINAL.

Application filed September 12, 1922. Serial No. 587,653.

To all whom it may concern:

Be it known that I, LEWIS J. GREENAWALT, a citizen of the United States, and a resident of Mansfield, in the county of Richland and State of Ohio, have invented a new and useful Improvement in Cartridge-Heater Terminals, of which the following is a specification.

My invention relates to electrically-heated devices and particularly to cartridge heaters.

The object of my invention is to provide a relatively simple and rugged terminal structure for a cartridge heater that shall prevent pulling and twisting action on the ends of the resistor wire.

In practicing my invention, I provide a refractory insulating member located adjacent to one end of a tubular metallic casing containing a heating element. The insulating member has a plurality of openings extending longitudinally therethrough and a plurality of laterally extending grooves in the inner face thereof, said grooves communicating with said openings. Tubular terminal members having integral laterally extending wing portions, are located in the openings, and the ends of the resistor and of the supply circuit conductors are suitably secured thereto. Means integral with the casing serve to hold the refractory insulating member in its proper operative position in the casing.

In the single sheet of drawings, Figure 1 is a view, in longitudinal section, of an electric heater comprising the device embodying my invention;

Fig. 2 is a top plan view of the device illustrated in Fig. 1;

Figs. 3 and 4 are top, plan and side elevational views, respectively, of a refractory member comprising a part of the device embodying my invention;

Fig. 5 is a fragmentary view in longitudinal section of an electric heater illustrating a securing means, and

Figs. 6 and 7 are views, in front and in end elevation, respectively, of a terminal member comprising a part of the device embodying my invention.

A cartridge heater designated generally by the numeral 11 comprises an outer tubular metallic casing 12, at one end of which there is suitably secured thereto, as by brazing, an end cap 13. A supporting member

14, which may comprise an elongated tubular member of a suitable refractory electrical non-conducting material, is located within the tubular member 12 and has wound thereon a suitable resistor member 15. In order to provide means for conducting the heat from the resistor member to the tubular casing, a quantity 16, of a suitable granular, electric-insulating and heat-conducting material, such as alundum, is placed within the casing 12 in such quantity as to occupy substantially all of the space not otherwise occupied by the resistor member and its supporting means.

At the open end of the casing 12, I provide a refractory insulating member 17, of disk form, which has a plurality of openings 18 extending therethrough and located in spaced apart relation relatively to each other. On the inner surface of the member 17 there is provided a plurality of parallel grooves 19 each of which communicates with one of the openings 18.

Terminal members 21, comprising a tubular portion and a plurality of laterally-extending wing portions integral therewith, are located in the openings 18, the wing portions being located in the grooves 19 and the tubular portions in the openings 18. The members 21 may be constructed from sheet metal punched and formed to substantially the shape illustrated in Figs. 6 and 7 of the drawings. The end portions 22 of suitable supply circuit conductors are located within the tubular portions of the terminal members 21 as are also the respective ends 23 of the resistor member 15, both end portions being suitably secured therein, as by soldering or brazing.

It is not essential to the carrying out of my invention that the members 22 constitute the ends of supply circuit conductors, as they may constitute relatively large terminal members for the cartridge to which the supply circuit and conductors may be suitably secured.

Means for maintaining the member 17 in its proper operative position adjacent to and within the end of the tubular member 12 comprise bent-over portions 24 of the tubular casing 12. Any suitable or desired number of these struck-in portions 24 may be employed. If necessary, or desirable, the outer surface of the member 17 may be located a short distance below the outer edge 110

of the tubular casing 12 and the space above the member 17 may be filled with a mass 25 of a suitable heat resisting cement.

The tubular member 21, located as hereinbefore described in the refractory insulating member, provides a terminal construction which prevents a pull upon the terminals or ends 22 being imparted to the end portions 23 of the resistor, thereby preventing a breaking effect thereon. The wing portions of the terminal members 21 prevent also a turning movement of not only the terminal members but also of the ends 23 of the resistor members whereby damage due to pulling or twisting of the ends of the resistor member is substantially entirely prevented.

Various modifications may be made in my invention without departing from the spirit and scope thereof, and I desire, therefore, to be limited only by the scope of the appended claims.

I claim as my invention:

1. A terminal construction for an electrically heated device having an electrical heating element associated therewith, comprising a refractory insulating member, and a terminal member for said heating element located in said insulating member and having integral means for preventing a turning movement thereof relatively to said insulating member.

2. A terminal construction for an electrically heated device having an electrical heating element associated therewith, comprising a refractory insulating member, and a terminal member for said heating element located in said insulating member and having integral means for preventing longitudinal and turning movements thereof relatively to said insulating member.

3. A terminal construction for an electrically heated device having an electrical heating element associated therewith, comprising a refractory insulating member hav-

ing an opening extending longitudinally therethrough and a groove in one surface thereof, and a tubular terminal member for said heating element located in said opening and having integral laterally extending wing portions located in said groove.

4. A terminal construction for an electrically heated device having a casing, a refractory supporting member therein and a resistor on said supporting member, comprising a refractory insulating member in said casing adjacent to one end of said refractory supporting member, said insulating member having an opening extending longitudinally therethrough and a laterally extending groove in one face thereof, and a tubular terminal member for said heating element located in said opening and having integral laterally extending wing portions located in said groove, integral portions of one end of said casing being struck in to hold said refractory insulating member in proper operative position in said casing.

5. In an electrical heating device, the combination with a tubular casing, a refractory supporting member therein and a resistor on said supporting member, of a refractory insulating member located within said casing at one end thereof, said insulating member having a plurality of openings extending longitudinally therethrough and a plurality of laterally extending grooves in the inner face thereof and said grooves communicating respectively with said openings, tubular terminal members for said resistor located in said openings and having integral laterally extending wing portions located in said grooves, and means integral with said casing for holding said refractory insulating member in its proper operative position in said casing.

In testimony whereof, I have hereunto subscribed my name this 5th day of Sept., 1922.

LEWIS J. GREENAWALT
